UNITED STATES PATENT OFFICE.

MARTIN W. PAULING, OF DOVER, MISSOURI.

REVERSING-GEAR.

1,120,078.

Specification of Letters Patent.

Patented Dec. 8, 1914.

Application filed December 4, 1913. Serial No. 804,610.

To all whom it may concern:

Be it known that I, MARTIN W. PAULING, a citizen of the United States, residing at Dover, in the county of Lafayette and State 5 of Missouri, have invented certain new and useful Improvements in Reversing-Gear; and I do hereby declare the following to be a full, clear, and exact description of the invention, such as will enable others skilled in 10 the art to which it appertains to make and use the same.

This invention relates to valve operating mechanism for reversing the slide valves of steam engines.

15 It is specially adapted for use in connection with traction engines, and it consists in the novel construction and combination of the parts hereinafter fully described and claimed.

20 In the drawings, Figure 1 is a front view of a reversing gear constructed according to this invention. Fig. 2 is a plan view; and Fig. 3 is an end view of the same.

A supporting frame 2 is provided and is 25 of any approved construction. The crank shaft 3 is journaled in suitable bearings in the frame, and an eccentric 4 is secured upon it in a suitable position to operate the valve-spindle 5. The valve-spindle 5 is pivoted 30 by a pin 6 to one end of a parallel motion 7 formed in any approved way and preferably provided with parallel horizontal members 8, the lower of which is secured to the frame and which is pivotally connected with the 35 upper member by vertical bars 9.

The eccentric is provided with an eccentric-strap 10 having a projecting arm 12 which is arranged diagonally of the axis of the valve-spindle. A connecting-rod 14 is 40 pivoted by a pin 15 to the middle part of the arm 12, and the other end of the connecting-rod is pivoted by a pin 17 to the opposite end of the parallel motion from the pivot of the valve-spindle.

45 The reversing handle 18 is secured to one end of a shaft 19 which is pivoted in the frame, below the level of the crank shaft, and it is provided with any approved catch mechanism for holding it stationary, such as 50 a toothed quadrant 21 and a pawl 22.

A reversing lever 24 projects from the

shaft 19, and 26 is a link which is pivoted by a pin 25 to the free end of the arm 12 on the eccentric-strap. The other end of the link 26 is pivoted by a pin 27 to the upper 55 end of the reversing lever 24. The lever 24 is arranged crosswise of the axis of the valve-spindle 5, and in that respect it is similar to the eccentric arm 12, although these two parts are not parallel, and the 60 link which connects them pivotally is arranged diagonally between their opposite end portions. The ends of the link 26 and the connecting-rod 14 are made adjustable so that all lost motion can be taken up. 65 When the reversing lever 24 is arranged substantially vertically, as shown in the drawings, the valve gear is adapted for one direction of motion of the engine and its crankshaft. The direction of motion is re- 70 versed by moving the reversing lever 24 downwardly to the right in Fig. 1 to a substantially horizontal position, so that the position of the strap on the eccentric is 75 changed.

What I claim is:

1. In a reversing gear, the combination, with a valve-spindle, and a driving-shaft; of an eccentric secured on the driving shaft and provided with a strap having an arm 80 which projects crosswise of the valve-spindle, a reversing rock-shaft arranged adjacent to the free end of the said arm, a reversing lever secured to the rock-shaft and also projecting crosswise of the valve-spindle 85 but in the opposite direction to the said arm, a reversing handle also secured to the rock-shaft, a link arranged diagonally between and pivoted to the said arm and reversing lever, and intermediate connections 90 between the said arm and the valve-spindle.

2. In a reversing gear, the combination, with a valve-spindle, and a driving shaft; of an eccentric secured on the driving shaft and provided with a strap having an arm 95 which projects crosswise of the valve-spindle, a reversing rock-shaft arranged adjacent to the free end of the said arm, a reversing lever secured to the rock-shaft and also projecting crosswise of the valve-spindle but 100 in the opposite direction to the said arm, a reversing handle also secured to the rock-

shaft, a link arranged diagonally between and pivoted to the said arm and reversing lever, a connecting-rod pivoted to the said arm, and a parallel link motion arranged 5 between the said connecting-rod and the valve-spindle.

In testimony whereof I have affixed my signature in the presence of two witnesses.
MARTIN W. PAULING.
